UNITED STATES PATENT OFFICE.

ALFRED STEPHEN KING, OF NORWICH, ENGLAND.

BOX-LID-NAILING MACHINE.

1,074,800.

Specification of Letters Patent.

Patented Oct. 7, 1913.

Application filed November 8, 1912. Serial No. 730,215.

To all whom it may concern:

Be it known that I, ALFRED STEPHEN KING, a subject of the King of Great Britain, residing at Hollinsclough, Eaton 5 Road, Norwich, in the county of Norfolk, England, have invented new and useful Improvements in Box-Lid-Nailing Machines, of which the following is a specification.

This invention relates to improvements in 10 box lid nailing machines which are especially applicable for securing the lids of boxes made in accordance with my former Patent No. 1,026,679, granted May 21, 1912.

According to this invention the portable 15 nailing machine comprises a standard or frame carrying a nail chute, at the bottom of which is a nail chuck or holder, and a nail plunger or hammer for driving the nails from the nail chuck. The standard or frame 20 is supported on the lid of the box by base plates and is held up to the side or end of the box by a downwardly extending stop or jaw secured to one end of one or both of the base plates which by slotted adjustment 25 serves as a gage to enable the machine to be held in proper position for a nail to be driven at the place required through the lid of the box and into its side or end. This stop or jaw has a recessed face which allows 30 a projecting lid to overhang the side of the box.

The drawings show two machines made in accordance with this invention.

Figure 1 is a side elevation. Fig. 2 is a 35 front elevation partly in section. (In both these views the nail plunger is shown in its lowest position). Fig. 3 is a view of the lower part of the nail chute, before the plunger has been depressed, of one machine. Fig. 4 is a side elevation. Fig. 5 is a part 40 vertical section. Fig. 6 is a part front elevation. Fig. 7 is a front elevation partly in section. Fig. 8 is a plan of another machine. Fig. 9 shows the jaw for engaging the bottom of the box.

a is a standard for a nail plunger *b* which is secured to a head *c* by screws *c'* and *c''*. Between the bottom of the head and the top of the frame is an india rubber buffer *d*. 50 Upon the standard *a* is a nail chute *e* leading through a mouth *e'* to a nail chuck. The chuck is made in two parts *f'* *f''* pivoted at *f''* *f''* the parts being continually pressed together by springs *f''* *f''* contained in thimbles *f''* *f''*. A piece *e''* is attached by a hook *e''* to a bar *e''* in order that the piece may be easily

removed if a nail should jam. The piece *e''* is held at its foot by a spring *e''*. The standard *a* is supported on the lid *g* of the box of which *g'* is the side by base plates *h* 60 secured to hooked projections *h'* *h''* at the lower end of the standard by nuts *h''* *h''* on screw bolts *h''* *h''*. A downwardly extending stop *i* which engages with the side *g'* of the box is also secured by the nut *h''*. The 65 stop *i* is preferably formed with a recessed face *i'* which allows a projecting lid to overhang the side of the box.

In using the machine the base plates *h* and stop *i* are first set at the desired gaged distance and angle. The standard is held by the left hand and pressed against the box. A nail *j* is dropped into the chute *e* and is driven into the lid by depressing the head *c*.

In the machine shown in Figs. 4 to 8 the 75 shape of the standard *a* is modified but the nail chute and nail chuck are of similar construction. The plunger *b* is connected by pins *b'* *b''* to links *b''* *b''* which are connected by pins *b''* *b''* to a bell crank lever *k* 80 pivoted at *k'* to the frame. The base plates *h* and the downwardly extending jaw *i* are secured together at the desired angle and at the desired distance apart by nuts *h''* *h''* on the bolts *h''* *h''*. 85

To the downwardly projecting stop *i* in either of the machines shown may be pivoted at *i'* an arm *i''* which carries upon it a jaw *i'''*. The jaw is adjustably secured to the arm *i''* by a screw *i''*. A spring *i''* constantly presses 90 against a stud *i''* at the upper end *i''* of the arm. When the end *i''* is pressed against the box the arm moves about the pivot causing the jaw *i'''* to engage with the bottom of the box. Another jaw *l* for pressing 95 against the other side *g''* of the box is carried by a lug *l'* adjustably secured to a screw rod *l''*.

l'' is a spring held between the end of the lug and the shoulder *l''* of the jaw. The 100 rod *l''* is connected to a plate *l''* capable of sliding in slots *h''* in the base plates *h*.

l'' is a bell crank lever one end of which *l''* enters a slot in the plate *l''* while the other *l''* is acted upon by a cam *h''* on 105 the lever *k*. The jaw *l* is drawn toward the side of the box by the action of the lever *k* as the cam *h''* depresses the end *l''* of the bell crank lever *l''* causing the other end *l''* to move the plate *l''*. When the lever *k* is 110 moved back the spring *l''* causes the end *l''* to rise and so free the jaw *l*.

The nails *j* are contained in a hopper *m* pivoted to the frame at *m'* and connected to the lever *k* by link *m*². The nails issue from the hopper *m* to a nail supply channel 5 *n* at the bottom of which is a nail feed plate *o*. The feed plate *o* has on its periphery a number of notches *o'* of different size for use with nails of similar size and the feed plate *o* is carried by another plate *o*², 10 points *o*³ on which enter holes in the feed plate. The plates *o* and *o*² are held together by a spring *o*⁴. On the plate *o*² is a handle *o*⁵ which is held in the position shown by a spring *o*⁶. When the plates are turned a 15 nail is carried from the nail supply channel *n* to the nail chute *e* which as before leads to the nail chuck. A handle *p* is attached to the frame.

When using the machine, after the bolts 20 *h*⁹ and *h*¹⁰ have been properly adjusted to suit the distance from the edge of the lid and the direction it is desired to drive the nail, the handle *p* is held in the left hand and the machine is placed on the top of the box. 25 The handle *o*⁵ is pressed against the action of the spring *o*⁶ by the left thumb which causes a nail to be fed to the nail chuck. The lever *k* is then pulled toward the operator by the right hand. This causes the 30 plunger *b* to descend and at the same time causes the jaw *l* to grip the box. The nail hopper *m* being also connected to the lever *k* the hopper is lifted causing the nails to fall into the channel *n*.

35 What I claim is:—

1. A portable nailing machine constructed and arranged for nailing down the lids of boxes, comprising a standard carrying a nail chute, a nail chuck at the bottom of the 40 chute, a nail plunger reciprocable in the standard, supporting base plates at the lower end of the standard, a downwardly extending stop secured to one end of a base plate and located in a plane at a right angle 45 to the plane of the base plate, and means for

adjusting the position of the stop relatively to the base plate and for changing the angle of the supporting base plates relatively to the standard.

2. A portable nailing machine constructed 50 and arranged for nailing down the lids of boxes, comprising a standard carrying a nail chute, a nail chuck at the bottom of the chute, a nail plunger reciprocable in the standard, supporting base plates at the lower end of the standard, and a downwardly extending stop secured to one end of a base plate and having a recess arranged to receive the overhanging edges of the 55 lids.

60 3. A portable nailing machine constructed and arranged for nailing down the lids of boxes, comprising a standard carrying a nail chute, a nail chuck at the bottom of the chute, a nail plunger reciprocable in the standard, supporting base plates secured to the lower end of the standard, a downwardly extending stop secured to one end of a base plate, an arm pivoted to the downwardly extending stop, and a jaw carried by the 65 arm and constructed and arranged to engage with the bottom of the box.

4. A portable nailing machine constructed and arranged for nailing down the lids of boxes, comprising a standard carrying a nail 75 chute, a nail chuck at the bottom of the chute, a nail plunger reciprocable in the standard, a nail hopper, a lever actuating the nail plunger and the nail hopper, supporting base plates secured to the lower end 80 of the standard, a downwardly extending stop secured to one end of a base plate, and a jaw carried by the base plates and arranged to press the box against the downwardly extending stop, the said jaw being 85 arranged to be operated by said lever.

ALFRED STEPHEN KING.
